UNITED STATES PATENT OFFICE

155,708

DESIGN FOR A BRACE

James Innes, Pelham, Lipman Cohen, New Rochelle, and Lee Spatz, Hempstead, N. Y., assignors to British-Makes, Inc., New York, N. Y., a corporation of New York

Application August 30, 1945, Serial No. 121,749

Term of patent 3½ years

(Cl. D17—15)

To all whom it may concern:

Be it known that we, James Innes, Lipman Cohen and Lee Spatz, all citizens of the United States of America, and residents of the city of Pelham, county of Westchester, State of New York, city of New Rochelle, county of Westchester, State of New York, and Hempstead, Nassau County, State of New York, respectively, have invented a new, original, and ornamental Design for a Brace, of which the following is a specification, reference being had to the accompanying drawing, forming part thereof.

Fig. 1 is a front view of a brace showing our new design, it being understood that the parts shown in broken lines are to be completed in a manner as the full line showings.

Fig. 2 is an enlarged detailed view of a portion of the brace shown in Fig. 1;

Fig. 3 is an enlarged edge elevational view of the spring portion of the brace; and

Fig. 4 is an enlarged fragmentary rear view of the spring portion thereof.

We claim:

The ornamental design for a brace, substantially as shown and described.

JAMES INNES.
LIPMAN COHEN.
LEE SPATZ.
